(57) **CLAIM**

The ornamental design for a blank for forming a beverage dispensing container, as shown and described.

DESCRIPTION

FIG. 1 is a front and inside view showing my new design for a blank for forming a beverage dispensing container;

FIG. 2 is a rear and outside view thereof;

FIG. 3 is a right side elevation thereof;

FIG. 4 is a left side elevation thereof;

FIG. 5 is a top plan view thereof; and,

FIG. 6 is a bottom plan view thereof.

The broken lines shown in FIGS. 1 through 6 indicate lines of weakness at which the material of the blank for forming a beverage dispensing container can be separated and/or folded. The bolded lines shown in FIGS. 2 through 6 indicate locations where adhesive may be applied to the blank for forming a beverage dispensing container.
